United States Patent Office

Des. 193,528
Patented Sept. 4, 1962

193,528

ESCUTCHEON

Fred J. Russell, Los Angeles, and George B. Solovieff,
South Gate, Calif.; said Solovieff assignor to said Rus-
sell

Filed Dec. 4, 1961, Ser. No. 67,776

Term of patent 14 years

(Cl. D50—6)

FIGURE 1 is a front elevational view of an escutcheon showing our new design.

FIGURE 2 is a vertical sectional view on the line 2—2 of FIGURE 1.

FIGURE 3 is a front perspective view of the design on a reduced scale.

We claim:

The ornamental design for an escutcheon, as shown.
